UNITED STATES PATENT OFFICE.

LUDWIG HEILBRUNN AND FRITZ FRIESE, OF FRANKFORT-ON-THE-MAIN, GERMANY,
ASSIGNORS TO THE FIRM OF GOLDSCHMIDT & LOEWENICK, OF FRANKFORT-ON-
THE-MAIN, GERMANY.

LAST FOR BINDING UPPERS.

1,051,581.

Specification of Letters Patent. Patented Jan. 28, 1913.

Application filed December 12, 1911. Serial No. 665,318.

To all whom it may concern:

Be it known that we, LUDWIG HEILBRUNN and FRITZ FRIESE, subjects of the German Emperor, and residing at Mainzerland-
strasse 225/227, Frankfort-on-the-Main, in
the German Empire, have invented certain
new and useful Improvements in Lasts for
Binding Uppers, of which the following is
a specification.

- 10 The distinguishing feature of the new last
consists in that it has a bore extending close
to the waist from the sole to the ridge of the
span in a vertical or inclined direction,
which bore will serve to carry the pulling
15 string secured to the edge of the upper by
means of a zig-zag stitching from the sole
of the last to the ridge of the span, so that
it will be possible to draw the upper at all
points well down on the last by one single
20 pull at the end of the string.

In order to make our invention more
clear, we refer to the accompanying drawing,
in which similar letters denote similar
parts throughout the several views and in
25 which:—

Figure 1 is a longitudinal, vertical section
through a last constructed according to our
invention. Fig. 2 is a bottom view of the
last. Fig. 3 is a cross section through the
30 last, along the line A—B in Fig. 1. Fig. 4
is a plug employed for securing the string
in the bore.

The last is made in the usual manner
of wood or any suitable material of two
35 pieces *a* and *a'*, and *a* has the customary
hole *f* with its lining, with which the
last is fitted on a work rest for facilitating
the operation of work. Approximately at
40 its waist, as indicated by the section line
A—B, a bore *b* is provided extending from
the sole *b*² to the ridge of the span *a*² in a
vertical direction, as shown in the drawing.
This bore is flared at its lower, sole end and
45 there forms a rectangular channel *b*¹. The
string ends *d*¹, indicated in Fig. 2 by dot-
and-dash lines, of the string *d* threaded
through zig-zag stitches along the edge of
the upper, are passed from the sole of the
50 last through the flared mouth *b*¹ of bore *b*
to the ridge of the span. It is very im-
portant, that the bore *b* is flared toward
the sole end into a rectangular shape. This

will cause the string ends to be bent over
sharply and to extend a short distance, only
in a horizontal direction. This will also 55
limit the pulling in of the upper at the
waist and prevent the respective parts of
the upper being drawn too close to each
other, as would easily happen when elastic
60 materials are used for the uppers. The rec-
tangular shape of the mouth of the bore
will thus result in a limitation of the tight-
ening of the edge of the upper at the waist.
The said rectangular mouth of the bore is 65
preferably arranged with its longer side
crosswise to the longitudinal axis of the
last, as this will still further reduce the
horizontal length of the string ends.

In order to make the last as simple as
possible, and to admit of dispensing with
special holding devices for the string ends
emerging from the bore *b*, the upper mouth
of said bore is utilized for securing the ends
70 of the strings, after these have been pulled
taut, by a plug, Fig. 4, being introduced into
75 said mouth. This plug consists of a head *g*
and shank *i*, the diameter of which corre-
sponds with that of the bore *b*. It is thus
only necessary to force the plug into the bore,
whereby the ends of the string will be 80
pressed against the wall of the bore and be
thus secured by clamping. Without a suit-
able means for securing the taut string the
last cannot be used, as the string would im-
mediately slacken if released. 85

We claim:

A last having a bore extending close to
the waist from the sole to the ridge of the
span, and a plug adapted to be inserted into
the upper end of said bore, the lower por- 90
tion of the latter widening toward the sole
and forming a rectangular opening at its
mouth, the longer axis of said rectangular
opening lying at right angles to the longi- 95
tudinal direction of the sole, for the pur-
pose described.

In testimony whereof we affix our signa-
tures in presence of two witnesses.

LUDWIG HEILBRUNN.
FRITZ FRIESE.
